UNITED STATES PATENT OFFICE

130,165

DESIGN FOR A COMBINED WALLET AND CARD HOLDER

Simon P. Wolf, Philadelphia, Pa.

Application April 4, 1941, Serial No. 100,151

Term of patent 14 years

To all whom it may concern:

Be it known that I, Simon P. Wolf, a citizen of the United States, residing at Philadelphia, in the county of Philadelphia and State of Pennsylvania, have invented a certain new, original, and ornamental Design for a Combined Wallet and Card Holder, of which the following is a specification, reference being had to the accompanying drawings, forming part thereof.

In the drawings:

Fig. 1 is a plan view of the inside of a combined wallet and card holder embodying my new design; and

Fig. 2 is a perspective view thereof with card holder in partly folded position; and

Fig. 3 is a front elevational view of the wallet per se.

The back of the wallet and the card holder are plain. The pockets of the wallet are plain, and the border lines on the card holder represent stitching.

I claim:

The ornamental design for a combined wallet and card holder, substantially as shown and described.

SIMON P. WOLF.
